ROLF LJUNGKULL, OF MILWAUKEE, WISCONSIN, ASSIGNOR TO HARNISCHFEGER CORPORATION, OF MILWAUKEE, WISCONSIN, A CORPORATION OF WISCONSIN.

HITCH OR CLEVIS FOR DRAGLINE BUCKETS.

Application filed December 20, 1926. Serial No. 155,985.

This invention relates in general to excavating buckets and more particularly to hitches or clevises for dragline buckets.

One of the principal objects of the present invention resides in the provision on a dragline bucket of a hitch or clevis arrangement for the dragline which is rugged and durable in construction, which has a range of adjustment adequate to meet the needs of the dragline bucket, which may be conveniently and easily adjusted and which is so constructed and organized as to place the load and stress on parts best adapted to bear the same.

Another object is to provide a device of this character made up of a minimum number of parts and adapted to be manufactured and applied to the bucket at a comparatively slight expense.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a view in side elevation showing a bucket equipped with a pair of clevises or hitches embodying the present invention;

Fig. 2 is a fragmentary plan view of the bucket shown in Fig. 1;

Fig. 3 is a view in horizontal section on line 3—3 of Fig. 1;

Fig. 4 is a view in vertical section on line 4—4 of Fig. 3; and

Fig. 5 is a detail perspective view of one of the plates employed to make up the attaching bracket of the clevis.

Referring to the drawing wherein for the sake of illustration is shown one embodiment of the invention, the numeral 1 designates generally a dragline bucket. The bucket 1 has side walls 2 and at the forward end of each side wall a hitch or clevis 3 embodying the present invention is provided.

Each hitch or clevis comprises a bracket made up of a pair of side plates 4, one side plate 4 having its rearward portion fitted flush against the outer face of its side wall 2

of the bucket and the other side plate 4 having its rearward portion fitted flush against the inner face of the same side wall 2. The side plates 4 of each clevis are in this manner opposed and are rigidly secured in assembled relation with respect to each other and with respect to the bucket by means of rivets 5 passing through the side plates 4 and through the portion of the bucket interposed between these plates. As shown in the drawing, the forward portion of the side plates 4 of each clevis or hitch are thickened and project beyond the forward end of the side wall of the bucket on which they are mounted and these projecting portions of the side plates are spaced from each other and have their confronting walls formed with transversely aligned vertical slots 6. The forward wall of each slot 6 is provided with a plurality of grooves or arcuate recesses 7. Preferably, three recesses 7 are provided in each side plate 4 and are slightly spaced one above the other. The recesses of one plate are transversely aligned with the recesses of the other plate and the opposed recesses together constitute seats, as will hereinafter more clearly appear. Ribs 4^a are integrally formed with the side plates 4 to strengthen these plates.

Each bracket has a clevis, designated generally at 10, associated therewith, each clevis being of substantially U-shape and having legs 11 provided at their rearward ends with integral enlargements in the form of laterally directed bearing lugs or members 12, the bearing lugs 12 having rounded front faces 13 which cooperate with the seats constituted by the curved recesses 7. The forward ends of the legs 11 of the clevises are connected by means of a curved body portion 15. These legs 11 extend through and are freely shiftable in the space between the forward ends of the side plates 4. As clearly shown in Fig. 3, the forward portions of the clevises are offset inwardly.

For the purpose of preventing the bearing lugs 12 of the clevis from being displaced from operative relation with respect to the seat with which it is associated, a holding pin, designated at 16, is provided and is inserted through any one of a series of pairs

of openings 18 provided in the side plates of the bracket and through a socket 19 provided in the clevis and concentric with the curved bearing surface 13 thereof.

5 As clearly shown in Figure 4, the socket 19 is formed by transversely recessing the confronting portions of the legs 11 and the lugs 12, and while the socket thus formed has only partial angular extent, it has sufficient angular extent to retain the pin 16 therein. There is, however, clearance between the pin 16 and the wall of the socket to prevent any heavy strain from being taken by the pin 16. The bearing lugs 12 and their seats take all heavy strain.

It is to be understood that three sets of openings 18 are provided, that is, there is one pair of openings 18 for each pair of seats 7. Each pair of openings 18 is located 20 rearwardly of its seats and in horizontal alignment therewith. The pin 16 is releasably held in operative engagement with any pair of openings 18 by means of a nut 20 threaded on one end of the pin and secured 25 against accidental displacement by a cotter pin or the like, designated at 21.

To secure a vertical adjustment of the clevis it is necessary only to remove the pin 16 by taking off its nut 20 and pulling it 30 axially from its openings 18 and the socket 19 of the clevis. The clevis may then be moved rearwardly to disengage the bearing surfaces of the lugs 12 from the seat provided by the recesses 7 on which it has been 35 mounted. With these parts disengaged the clevis may be adjusted vertically to align it with any one of the seats, and after it has been associated with the desired seat, the pin 16 is reinserted and the nut 20 again 40 threaded on the pin to complete the adjustment. Assembly of the parts in the first instance is provided by virtue of the extension of the slots 6 entirely through the side plates.

45 With this construction, the load is taken on substantial portions of the bucket and clevis in all adjustments, and yet the clevis may swing freely in any adjustment and is adjusted along the bracket as may be desired.

The invention claimed is:

1. A hitch for dragline buckets comprising a bracket adapted to be secured to the bucket and having a plurality of vertically spaced internal seats, the structure of the bracket substantially enclosing said seats a clevis having means engageable with any one of said seats and means for preventing the clevis from being displaced from operative relation with respect to the seat with which it is associated.

2. A hitch for dragline buckets comprising a bracket made up of a pair of similar side plates having confronting slots extending only part way through the same in a

transverse direction and opening inwardly whereby the slots are substantially enclosed, said side plates also having a plurality of pairs of seats, a clevis having an enlarged rearward portion accommodated in the slots 70 of the side plates and having rounded surfaces selectively engageable with the seats, the forward ends of the side plates being spaced to accommodate the forward portion of the clevis, and means for holding the 75 clevis engaged with any one of the seats.

3. A hitch for dragline buckets comprising a bracket made up of a pair of similar side plates having confronting slots and a plurality of pairs of seats, a clevis having so an enlarged rearward portion accommodated in the slots of the side plates and having rounded surfaces selectively engageable with the seats, the forward ends of the side plates being spaced to accommodate the forward 85 portion of the clevis, and means for holding the clevis engaged with any one of the seats and comprising a pin, said clevis having a socket through which said pin is passed, said socket being larger than the pin to relieve the pin of any material strain, said plates having a plurality of pairs of transverse openings aligned with the seats with which the pin is selectively engageable.

4. A hitch for dragline buckets comprising a pair of side plates having their rearward ends adapted to be secured to the bucket, the forward ends of the plates projecting beyond the bucket and being formed with laterally and inwardly extending projections which extend towards but terminate in spaced relation with respect to each other, a clevis extending in between the inward lateral projections and having at its inner end lateral enlargements engaged with the inward projections of the plates to afford an operative connection between the clevis and the bracket and means for maintaining the operative connection between the clevis and the bracket.

5. A hitch for dragline buckets comprising a pair of similar side plates having their rearward ends adapted to be secured to the forward end of the side wall of the bucket, the forward ends of the plates projecting beyond the bucket and being provided with confronting slots and spaced forward extremities, the forward extremities having pairs of inwardly opening recesses of arcuate form, said recesses providing a plurality of vertically spaced seats, a U-shaped clevis disposed between the spaced forward extremities and having its legs formed at their rearward ends with enlargements having arcuate bearing surfaces cooperable with the seats, and means for holding the clevis engaged with any of the seats while permitting movement of the clevis on its seat.

6. A hitch for dragline buckets comprising a bracket adapted to be secured to the

110

115

120

125

130

bucket and made up of a pair of plates having their forward ends projecting beyond the bucket and provided with inwardly extending lateral projections recessed internally to provide a plurality of vertically spaced seats, and a clevis having rounded lugs engageable with the seats.

7. A hitch for dragline buckets comprising a bracket having an internal and substantially enclosed rounded seat and a clevis having an enlarged rear end portion provided with rounded lugs engageable with said seat.

8. A hitch for dragline buckets comprising a bracket having an internal rounded seat and a clevis having an enlarged rear end portion provided with rounded lugs engageable with said seat and means for preventing disengagement of the lugs of the

clevis from the seat of the bracket while permitting the lugs and seat to take all of the load and strain.

9. A hitch for dragline buckets comprising a bracket attached to the bucket and having an opening therein and also having a plurality of spaced rounded seats adjacent the opening, a clevis having an enlargement provided with a rounded bearing surface selectively engageable with the rounded seats, and separate and releasable positive means loosely interconnected with the clevis and bracket to prevent operative disassociation of the bearing surface from the selected seat while permitting the enlargement and bracket to take all the load.

In witness whereof, I hereto affix my signature.

ROLF LJUNGKULL.
